[57] CLAIM

The ornamental design for portable cooking and heating stove, as shown and described.

DESCRIPTION

FIG. 1 is a front elevational view of a portable cooking and heating stove showing my new design;

FIG. 2 is a front view thereof;

FIG. 3 is a right side view thereof;

FIG. 4 is a rear view thereof;

FIG. 5 is a bottom plan view thereof;

FIG. 6 is a top plan view thereof; and,

FIG. 7 is a perspective view thereof.

A central heat source compartment is covered by a heat-resistant glass plate which lies beneath four utensil supporting arms as shown best in FIG. 7.

FIG. 1

FIG. 3

FIG. 5

FIG. 2

FIG. 4

FIG. 6

FIG. 7
